UNITED STATES PATENT OFFICE.

JOSEPH ABETZ, OF NEW BRITAIN, CONNECTICUT.

ADJUSTABLE SHADE-BRACKET.

1,368,091.

Specification of Letters Patent.

Patented Feb. 8, 1921.

Application filed February 9, 1920. Serial No. 357,410.

To all whom it may concern:

Be it known that I, JOSEPH ABETZ, a citizen of the United States, residing at New Britain, in the county of Hartford and State 5 of Connecticut, have invented certain new and useful Improvements in Adjustable Shade-Brackets; and I do declare the following to be a full, clear, and exact description of the invention, such as will enable 10 others skilled in the art to which it appertains to make and use the same.

This invention relates to improvements in curtain shade fixtures or brackets, and has more particular reference to a bracket of 15 this type which is capable of being adjusted to accommodate shade-rollers of various lengths.

An object of the invention is to improve upon devices of this class by producing a 20 simple, inexpensive, yet highly efficient bracket, which may be quickly attached to, and detached from the window frame, the parts of the bracket being so connected and arranged that quick adjustment may be had.

Another object of the invention is to provide novel means for connecting the parts 25 of the bracket together in such a manner that accidental disconnection thereof will be prevented to a great extent, the parts of 30 the bracket being also constructed in such a manner that the means for securing the bracket in position on the window-frame, also serves as a means for preventing longitudinal movement of the sliding part of the 35 bracket, that is, said means retains this sliding part in a set position.

Other objects and advantages of the invention will be apparent during the course of the following description.

In the accompanying drawings forming a 40 part of this specification and in which like numerals are employed to designate like parts throughout the same,—

Figure 1 is an elevational view of a 45 bracket constructed in accordance with my invention, illustrating the same in position on a window frame.

Fig. 2 is a longitudinal section on the 50 plane of the line 2—2 of Fig. 1.

Figs. 3, 4, and 5 are detail perspective

views of the parts of the bracket disconnected.

In the drawings, wherein for the purpose of illustration is shown a preferred embodiment of my invention, the numerals 1 and 2 55 designate a pair of metal plates, the former of which may be termed the base plate, it being provided with a plurality of tongues 3, two of which are disposed at the extreme ends of the plate, and the others of which 60 are disposed between the ends of the plate, the last mentioned tongues being struck up from the plate in the manner shown. These tongues 3 extend laterally from the plate 1 and are designed to coact with the plate 2 65 to retain these plates together. The manner in which these tongues coact with the plate 2 is shown in Figs. 1 and 2. By reference to these figures it will be seen that this plate 2 is provided at its opposite ends with 70 notches 4, with which the end tongues coact, and it is further provided between its ends with openings 5 with which the other tongues coact. In other words, the tongues 3 are clenched against the plate 2 in the 75 manner shown. Furthermore, plate 2 is provided at its center with a longitudinal depressed portion 2^a, which provides a pair of offset flanges 2^b. The third part of the bracket which I have termed the bracket 80 carrying member, is designated by the numeral 6, and this member is adapted to be slidably mounted between the plate 1 and the flanges 2^b of the plate 2. Member 6 includes spaced strips 7 and 8 between which 85 the longitudinal depressed portion of the plate 2 is disposed. These strips are connected together at one of their ends by a laterally extending slotted flange 9, while at their opposite ends, they are connected 90 by means of the slotted bracket 10. This construction permits the plate 2 to extend through the slots formed in the parts 9 and 10, and as the plate 2 is provided along its opposite longitudinal edges with widened 95 portions which form stops 11, it will be seen that when either of the parts 9 and 10 engage these stops, sliding movement will be limited.

The assembled bracket will be held in po- 100

sition on the window frame in any suitable manner, such as for instance by means of wood screws 12. In order to permit the use of screws or other suitable fastening means, 5 I provide each of the plates 1 and 2 with holes 13 through which the screws are adapted to pass. Attention is called to the fact that the screws 12 not only serve to retain the bracket in position, but they also 10 serve as a means for preventing sliding movement of the member 6 after the same has been moved to the desired position to suit the shade roller with which it coacts. In other words, it will be seen that upon 15 tightening the screws sufficiently, the heads thereof will move the plates 1 and 2 into close proximity, thus binding the member 6 between the plate 1 and flanges 2^b in such a manner as to prevent further longitudinal 20 movement of said member.

A bracket constructed in accordance with my invention will be found extremely useful in that when the parts thereof are once assembled there will be little or no possibility 25 of them becoming disconnected and lost. In a sense, I have perfected a bracket which consists of one article, and it is equally as convenient as the simple one-piece non-adjustable bracket now in use, and is also more 30 advantageous than such a bracket because it is adjustable, which construction will permit it to be used in connection with shade rollers of various lengths. Not only is my bracket extremely useful in the above respect, but it is also advantageous in that the 35 sliding part may be quickly and readily moved to the desired position, because it is freely slidable. The construction is strong, the means for retaining the bracket in position 40 is novel, because of the already described reasons, and the bracket as a whole is highly efficient and inexpensive to both the manufacturer and the user.

In use, it will be seen that the member 6 45 may be moved longitudinally in either of two directions until the parts 9 or 10 engage the stops 11, thus permitting a considerable range of adjustment to be had, so that shade rollers of various lengths may be used. After the member 6 has been moved to a position 50 to accommodate the shade roller, the fastening screws 12 will be tightened, thereby forcing the flanges 2^b of the plate 2 toward the plate 1 and clamping the member 6 55 tightly between them. The parts will remain in this position until the fastening screws are removed.

From the foregoing description, taken in connection with the accompanying drawings, 60 it is believed that the use of my bracket and most important advantages thereof are obvious, therefore, further description is deemed unnecessary.

I claim:

65 1. A window-shade fixture comprising a

pair of attaching plates, one of said plates having tongues struck up from one of its faces, and being also equipped with spaced openings, the other plate also being provided with spaced openings, some of which are 70 adapted to receive said tongues which are clenched against the second named plate to retain both plates together, and the others of which are designed to register with the openings in the first named plate, said second 75 plate being also provided with stops on its longitudinal edges; a bracket carrying member longitudinally slidable between said plates, said bracket member including spaced strips, connected together at one 80 of their ends by a laterally directed slotted bracket portion and at their opposite ends by a slotted laterally bent flange which is designed to engage the stops and limit the sliding movement of the member 85 in one direction, while the bracket portion limits its movement in the opposite direction; and screws insertible through some of the openings in the plates to retain all the aforesaid parts in position. 90

2. A shade bracket comprising an apertured base plate, a second apertured plate connected thereto, the latter being provided with a longitudinal depressed portion forming offset flanges, and a bracket carrying member slidable between said base plate and offset flanges of the second named plate, said member including spaced strips between which said longitudinal depressed portion is disposed, thereby permitting said offset 95 flanges to contact said strips so that when the fastening members are passed through the apertures in the plates, the flanges will bind and hold the bracket member in position. 100

3. A window shade bracket comprising a 105 base plate, a second plate connected thereto, said last named plate being provided at its center with a longitudinal depressed portion which forms offset flanges which are in turn shouldered to provide stops, and a bracket carrying member slidable between the flanges and the base plate, said member including strips between which said depressed portion is arranged, a laterally extending slotted bracket arm connecting one of the 110 ends of said strips together, and a laterally extending slotted flange connecting the other ends of the strips together, the ends of said bracket carrying member extending through the slots in the arm and flange, which are intended to abut said stops and limit the movement of the member in opposite directions. 115

4. In a device of the class described, a plate having offset flanges on its longitudinal edges, stops projecting from opposite 120 side edges of said plate and intermediate the ends thereof, a bracket carrying member including a pair of spaced apart side bars 125 slidably engaged with said flanges, a bracket arm connecting one end of said bars and 130

having a slot adjacent its connection therewith to receive said plate, said arm being adapted to engage said stops to limit the movement of the member in one direction, 5 and an additional stop flange connecting the opposite ends of said side bars, said flange also having a slot therein to receive said

plate, said flange being adapted to engage said stops to limit the movement of the member in the reverse direction.

In testimony whereof I have hereunto set my hand.

JOSEPH ABETZ.
